UNITED STATES PATENT OFFICE

2,515,040

FUSE

John B. Hatcher, Chicago, Ill., assignor to the
United States of America as represented by the
Secretary of the Navy

Application December 1, 1947, Serial No. 789,129

1 Claim. (Cl. 102—72)

1

This invention relates to fuzes and is particularly directed to improvements in fuzes designed for use with rocket type projectiles.

A principal object of the present invention is to provide a fuze for a rotating rocket which is armed by centrifugal force and automatically fired after a predetermined time delay or at any time after arming upon impact.

A further object is to provide a fuze which is simple in construction, and operation and positive in function.

Still further objects, advantages, and improvements will be apparent from the following description of the invention taken in connection with the accompanying drawings wherein:

Fig. 1 is a front view in elevation of the present invention;

Fig. 2 is a view in section taken along the longitudinal axis of the fuze;

Fig. 3 is a fragmentary sectional view taken along 3—3 of Fig. 4;

Fig. 4 is a sectional view taken along 4—4 of Fig. 2;

Fig. 5 is a sectional view taken along 5—5 of Fig. 2.

Referring now to the drawings in which like numerals of reference are employed to designate like parts throughout the several views, and more particularly to Figs. 1 and 2, the numeral 1 refers to an annular base body having a threaded extension 1a at its base adapted to fit into the nose of a rotating rocket (not shown). The base end of the bore through the body 1 receives a detonator holder plate 2 in which is seated a centrally located detonator 3. The plate 2 is covered by a disk 4 which in turn covers and is secured to one end of a rotatable cylindrical relay detonator housing 5 extending through the forward side of the body 1. The relay detonator housing 5 is provided with a central bore 6 which alines with a bore 6a in the disk 4 which registers with the detonator 3.

Grouped around the central bore 6 is a series of axially directed relay detonator bores 7. Each relay detonator bore receives a delay detonator unit 8. In place of one of the bores 7 the relay detonator housing is provided with a blind hole 10 in its forward end. Any one of the delay detonator units 8 is adapted to register with a lateral passage 9 extending through the disk 4 and communicating with the bore 6a in the detonator 3.

The base body 1 is covered by an intermediate body 11, the base end of which caps the housing 5 and is rotatably interlocked with the base housing 1 by a locking ring 12. The intermediate body

2

11 is provided with a small longitudinal bore 13 which alines with the bore 6. The bore 13 is intersected by a transverse bore and a transverse socket. In the transverse bore is a pair of opposed centrifugal release plungers 14 backed on their radiating outer sides by springs 15. The inner ends of the plungers 14 are pointed to fit in the transverse bore 16 of a stem 17 carried by a latch stud 18 fitting the transverse socket. Normally the radially inner ends of the plungers 14 hold the stud 18 against radial movement. When the stud is in its radially inner position, it secures a key ball 19 in position to restrain a detonator pin 20 mounted in a hole 21 extending axially in the intermediate body 11 and adapted to register with any one of the delay detonator units 8 or the blind socket 10. The detonator pin is backed by a spring 22.

The intermediate body 11 is covered by an outer body 23 likewise having a central bore 24 therein. The inner or base end of the bore 24 receives a detonator 25. The outer end of the bore 24 receives a detonator plunger 25a having a head 26 covered by a light cap 27. The bore 24 is intersected by a transverse bore which carries a pair of centrifugal release pins 28 backed at the radially outer sides by springs 29.

The operation of the fuze is as follows:

The fuze is normally set so that the blind socket 10 alines with the detonator pin 20 (Fig. 3). The centrifugal release plungers 14 hold the stud 18 in its radially inner position thereby locking the detonator pin 20 in its forward position against spring 22 through the agency of the key ball 19.

Before firing the rocket the intermediate body 11 is rotated manually from the initial or safety position (as in Fig. 1) to any of the several positions (1, 2, 3, 4, 5, in Fig. 1) alining a corresponding delay detonator 8 with the detonator pin 20. The delay detonator units are designed to provide a selective time delay.

When the rocket is fired, centrifugal force forces the release plungers 14 radially releasing the latch stud 18 which is then likewise thrown radially by centrifugal force to release the key ball 19 whereupon the detonator pin 20 immediately pierces the delay detonator unit 7 alined therewith. After a delay, as determined by the delay detonator, detonator 3 is fired which in turn operates an auxiliary detonating fuze in the rocket head.

Also when the rocket is launched, the centrifugal release pins 28 move radially freeing the detonator plunger 25 so that the detonator plunger 55 will fire on impact as long as the rotation of the

rocket is above the critical speed necessary to hold released the centrifugal release pins 28.

While the invention has been described with reference to a certain preferred example thereof which gives satisfactory results, it will be understood by those skilled in the art to which the invention pertains, after understanding the invention, that various changes and modifications may be made without departing from the spirit and scope of the invention, and it is my intention therefore to cover in the appended claim all such changes and modifications.

What I claim as new and desire to be secured by Letters Patent is:

A fuze comprising a turnable detonator housing, chambered to accommodate plural detonator units, a base member of essentially tubular form, closure means heading one end of said member, resulting in a cylinder, said closure means having a lateral passage with which one of the chambers is registerable, said detonator housing fitting the cylinder and projecting forwardly of the base member, an outer body and an intermediate body secured together, said intermediate body being recessed to match the cylinder and being attached to the base member to contain the projection of the detonator housing, said bodies, housing and closure means having a common central bore with which the lateral passage communicates and being obstructed by detonators in the respective closure means and outer body, sets of centrifugally operable detents directed into the axis of the bore and consisting of pairs in the

respective outer and intermediate bodies oriented perpendicularly to each other and situated in front and back of the detonator position in the outer body, a spring-loaded detonator pin carried by the intermediate body in line with a selected detonator chamber, means locking said pin in retracted position, said means including a centrifugally displaceable stem initially held in blocking position across the bore through impalement by the respective pair of detents, and a detonator plunger carried by the outer body in front of that respective pair of detents.

JOHN B. HATCHER.
